UNITED STATES PATENT OFFICE.

CHARLES E. VAWTER, JR., OF BLACKSBURG, VIRGINIA.

INDEX FOR RECORDING INSTRUMENTS.

No. 872,391.

Specification of Letters Patent.

Patented Dec. 3, 1907.

Application filed August 24, 1906. Serial No. 331,895.

To all whom it may concern:

Be it known that I, CHARLES E. VAWTER, Jr., a citizen of the United States, residing at Blacksburg, in the county of Montgomery 5 and State of Virginia, have invented certain new and useful Improvements in Indexes for Recording Instruments, of which the following is a specification.

This invention relates more particularly 10 to improvements in movable indexes for recording instruments, such for example as the kind forming the subject of U. S. Letters Patent No. 807,518, granted to me December 19, 1905. In instruments of this character the record is produced upon a moving record sheet by means of a marking device carried upon an index arm pivoted at or near one end so that the marking device may be moved angularly across the record sheet, the 15 20 said marking device being normally out of contact with the record sheet and is drawn into engagement therewith periodically.

The object of the present invention is to increase the efficiency of this class of instruments by providing an index which is more dead beat or aperiodic, having a smaller moment of inertia, quicker in action and more sensitive than any with which I am acquainted.

30 One form of my invention is shown in the accompanying drawings wherein;

Figure 1, represents the said device in side elevation; Fig. 2, a top plan view thereof; and Fig. 3, a detail sectional view taken 35 along the line 3—3 of Fig. 1.

Referring to the accompanying drawings, 1 represents the index arm which is preferably of some light metal not possessing a high degree of flexibility; 2 a pivot spindle 40 which passes transversely through and is made fast to the body of the index arm, by friction between the two or otherwise, near one end thereof, the said index arm being thickened at that portion to accommodate 45 the spindle, as shown in Fig. 3. The pivot spindle 2 is mounted in pivot bearings 3 and 4 in a circular yoke 5, formed on a pivot spindle 6, which may be mounted in any suitable pivot bearings 7. The bearing 4, as 50 will be seen, may be in the form of an adjustable screw. Extending rearwardly from one side of this spindle 6 is an arm 8 to which is secured a spiral spring 9, which latter is in turn secured at its upper end to one end of 55 the index arm. This arm 8 also carries an adjusting screw 10, which; engaging a soft

rubber buffer 11 on the lower side of the rearward extension of the index arm, limits the downward movement of said extension. The arm 8 is also provided with a 60 screw threaded extension 12 upon which is mounted for adjustment a counter-balance weight 13.

The free end of the index arm has attached thereto a small soft iron armature 14 for attraction by a record producing magnet 15, such, for example, as shown in the above mentioned patent. Upon the same end of the index arm is mounted a small metal collar 16. Extending through this collar, the 70 end of the index arm and the armature 14, is an ink receptacle 17 having a substantially conical bottom 18 through which passes an outlet 19 for the passage of the ink.

20 represents the record sheet. The marking device is pulled into engagement with the record strip by the magnet 15, against the tension of the spring 9, and is instantaneously withdrawn by said spring from the record sheet upon the release of the armature 14, 80 by the magnet. If the resiliency of the index arm is depended upon to allow the marking device to be drawn to the record sheet and to remove the said device from said sheet, there occurs a continued springing action of the index arm, which materially interferes with the accuracy of the instrument. This arrangement of spring with soft rubber buffer 11 deadens this springing action. With the present arrangement, the movement of the recording device becomes practically dead beat, when periodically drawn to engage the record sheet. The arrangement shown also permits the recording end of the index to yield more readily to the attractive 95 force of the magnet, thereby rendering the instrument more sensitive.

The counter balance weight 13 equalizes the wear on the pivots of the spindle 6, and makes the index in equilibrium in any position.

The index herein shown and described is only one of several specific forms which my invention may assume without departing from the spirit thereof.

Having thus described a form of my invention, what I claim is:

1. A support mounted for angular movement upon an axis, an index arm fulcrumed on said support substantially in the line of 110 said axis for angular movement in a direction at right angles to the axial movement of said

support, and recording means carried by said arm.

2. A support mounted for angular movement on an axis but rigid against movement 5 in a direction at right angles to said axis, an index arm pivoted at one point only on said support for movement in a direction at right angles to the axial movement of said support, resisting means to oppose the said movement 10 of said arm in one direction and assist it in the opposite direction; and recording means carried by said arm at its free end.

3. A support mounted for angular movement upon an axis, an index arm fulcrumed 15 in said support for angular movement in a direction substantially at right angles to the axial movement of said support, cushioning means to limit the angular movement of said arm in its fulcrum in one direction, resisting 20 means acting against said movement in the opposite direction, and recording means carried by said arm near one end, the said fulcrum of said arm being between said recording means and the point where said resisting 25 means acts on said arm.

4. A spindle pivoted for angular movement on its longitudinal axis, an index arm pivotally supported near one end by said spindle for angular movement in a direction 30 substantially at right angles to the axial movement of said spindle, a projection movable with said spindle, a stop carried by said projection to limit the movement of said index arm in one direction, a spring connected 35 to said projection and to said index arm near one end thereof, and recording means carried by said arm near its other end.

5. A supporting yoke mounted for angular movement on a diametrical axis, an index 40 arm pivotally mounted near one end in said yoke for angular movement in a direction substantially at right angles to the axial movement of said yoke, an arm movable with said yoke, a stop carried by said arm to limit 45 the movement of said index arm in one direction, a spring connected to said stop-carrying arm and to said index arm near one end thereof to oppose the movement of said index on its pivot in one direction, and recording 50 means carried by said index arm near its other end.

6. A supporting yoke, pivot spindles extending from diametrically opposite sides of 55 said yoke to support said yoke for angular movement, an index arm pivotally mounted near one end in said yoke for angular movement in a direction substantially at right angles to the angular movement of said yoke on its pivots, an arm extending outward from 60 said yoke and movable therewith, a stop carried by said arm to limit the movement of said index arm in one direction, a spring connected to said stop-carrying arm and to said index arm near one end thereof to oppose the angular movement 65 of said index arm on its pivots in one direction, an adjustable counter-balance weight mounted on said stop-carrying arm, and recording means carried by said index arm on its

pivots in one direction, an adjustable counter-balance weight mounted on said stop-carrying arm, and recording means carried by said index arm near its other end.

7. A pivotal support, an index arm pivotally mounted in said support in the line of the pivotal axis thereof for angular movement in a direction substantially at right angles to the axial movement of said support, a stop to limit the angular movement of said arm on its pivot in one direction, a yielding body on said index arm to engage said stop, and yielding means acting against the pivotal movement of said arm in the opposite direction.

8. A supporting yoke mounted for angular movement on a diametrical axis, an index arm pivotally mounted near one end in said yoke for angular movement in a direction substantially at right angles to the axial movement of said yoke, an arm movable with said yoke, a stop carried by said arm to limit the movement of said index arm in one direction, a resilient buffer carried by said index arm to engage said stop, a spring connected to said stop-carrying arm and to said index arm near one end thereof to oppose the movement of said index on its pivot in one direction, and recording means carried by said index arm near its other end.

9. A supporting yoke, pivot spindles extending from diametrically opposite sides of said yoke to support said yoke for angular movement, an index arm pivotally mounted near one end in said yoke for angular movement in a direction substantially at right angles to the angular movement of said yoke on its pivots, an arm extending outward from said yoke and movable therewith, a stop carried by said arm to limit the movement of said index arm in one direction, a soft rubber buffer carried by said index arm to engage said stop, a spring connected to said stop-carrying arm and to said index arm near one end thereof to oppose the angular movement of said index arm on its pivots in one direction, an adjustable counter-balance weight mounted on said stop-carrying arm, and recording means carried by said index arm near its other end.

10. The combination with a support mounted for angular movement upon an axis of an index arm pivotally mounted on said support, a spring acting against the angular movement of said arm on said pivot in one direction, and recording means carried by said arm, the pivot of said arm being between the said recording means and the point where said spring acts on said arm.

11. The combination with a support mounted for angular movement upon an axis, of an index arm pivotally mounted on said support, a spring acting against the angular movement of said arm on said pivot in one direction, recording means carried by

said arm on the opposite side of said pivot from the point where said spring acts on said arm, and a weight on the opposite side of said pivot and said axis from said recording means to counterbalance the weight of the arm and recording means.

12. The combination with a support mounted for angular movement upon an axis, of an index arm pivotally mounted on 10 said support, means acting against the angular movement of said arm on said pivot in one direction and with it in the opposite di-

rection to restore said arm to its normal position, and recording means carried by said arm, the pivot of said arm being between the 15 said recording means and the point where said restoring means acts on said arm.

In testimony whereof I affix my signature in presence of two witnesses.
